[57] CLAIM

I claim the ornamental design for a chandelier, as shown and
described.

DESCRIPTION

FIG. 1 is a perspective view of a chandelier showing my new
design;

FIG. 2 is a front elevational view of the chandelier, the rear
elevational view being a mirror image;

FIG. 3 is a left side elevational view of the chandelier;

FIG. 4 is a right side elevational view of the chandelier;

FIG. 5 is a top plan view of the chandelier; and,

FIG. 6 is a bottom plan view of the chandelier.

The broken lines shown are for illustrative purposes only
and form no part of the claimed design.
